BY Munn & C

ATTORNEYS,

UNITED STATES PATENT OFFICE.

THOMAS V. FORSTER, OF NEW Utrecht, NEW YORK.

DESIGN FOR A HOSE-REEL SPOOL.

SPECIFICATION forming part of Design No. 21,622, dated June 14, 1892.

Application filed April 29, 1892. Serial No. 431,220. Term of patent 14 years.

To all whom it may concern:

Be it known that I, THOMAS V. FORSTER, a citizen of the United States, residing at New Utrecht, in the county of Kings and State of New York, have invented and produced a new and original Design for a Hose-Reel Spool, of which the following is a specification, reference being had to the accompanying drawing, which is a perspective view of a spool showing my design.

The leading feature of my design consists in the representation upon the side of the spool of a central circle, an outer ring, and a star, the points of which extend between the central circle and outer ring. The central

circle A is concentric with the outer circle or ring B, and the points or arms C of the star extend between the central circle and the outer ring and produce the effect of a star supported and radiating from a circular center and surrounded and connected at its points by the outer circle or ring. 20

I claim—

The design for a hose-reel spool, herein shown and described.

THOMAS V. FORSTER.
